UNITED STATES PATENT OFFICE.

DAVID POWELL, OF CHICAGO, ILLINOIS.

COMPRESSOR FOR REFRIGERATING APPARATUS.

Application filed April 4, 1923. Serial No. 629,793.

My invention relates to a compressor for refrigerating apparatus particularly of the compression type wherein a liquefiable gas such as ammonia is mechanically compressed for cooling or refrigerating purposes. I consider the several features of my invention to be useful in any apparatus of the type mentioned but they are particularly useful in the small units intended for use in connection with domestic refrigerators.

One of the objects of my invention is the provision of a compressor for refrigerating apparatus which will be of simple and compact construction, inexpensive to manufacture, reliable in operation, which may be readily installed in connection with a refrigerator box, operated economically, and which will require but a minimum of attention.

A further object of my invention is the provision of a machine for compressing the refrigerant which will operate substantially noiselessly. It is essential that the refrigerant be compressed to a relatively high pressure. Heretofore, the valve which controls the flow of the high-pressure refrigerant from the compressor cylinder has been so constructed that, upon the piston commencing its return or nonworking stroke, it has been slammed down against its seat and this has been the cause of considerable noise. My invention aims to provide a valve so constructed that it will be cushioned by a quantity of the high-pressure refrigerant being trapped under it and thus prevent it from violently striking its seat. Notwithstanding the use of several rings on the piston of the compressor, the high-pressure refrigerant does tend to leak around the piston and pass into the crank case of the compressor. The oil in the crank case, being churned by the crank shaft and the connecting rod, upon becoming contaminated by the refrigerant, begins to foam and thus a pressure builds up in the crank case causing the crank shaft, connecting rod and piston to knock, which not only creates considerable noise but seriously affects proper lubrication of the parts and necessitates frequent filling of the crank case with oil. My invention also aims, therefore, to provide means whereby these conditions will be obviated, preferably by providing a passage-way for the refrigerant to escape from the crank case to the low-pressure portion of the refrigerant circulatory system.

It is essential, of course, that the piston and the cylinder walls of the compressor be kept well lubricated while the compressor is operating, and, as the refrigerant comes into contact with the lubricated cylinder walls when being compressed, it absorbs at least some of the oil. If the oil in the refrigerant is not removed before the refrigerant passes into the expansion coil, said coil becomes insulated by the oil depositing on the inner surface thereof and the efficiency of the apparatus is reduced materially. It is a further object of my invention, therefore, to provide novel means for separating the oil from the high-pressure refrigerant before it passes into the expansion coil, said means preferably comprising a chamber in which a plurality of inverted spaced cone-shaped screens of fine mesh are disposed for collecting the oil present in the refrigerant as the latter flows upwardly through the screens.

It is a further object of my invention to provide means for returning the oil separated from the refrigerant to the crank case of the compressor so that it may again be used for lubricating purposes, this object preferably being accomplished automatically and without permitting the high-pressure refrigerant to flow into the crank case. I preferably attain these results by providing valve-controlled means for the oil to flow from the chamber containing the oil separator to the crank case, the valve being operated by a piston located in another chamber through which the refrigerant passes, the arrangement being such that, when the pressure of the refrigerant exceeds a predetermined point, it may circulate freely through the refrigerant circulatory system, said valve in that case being closed but, when the pressure of the refrigerant drops below a predetermined point, the flow of the refrigerant into the oil separator is checked, the valve in said latter case being opened.

The invention consists in the novel constructions, arrangements and devices to be hereinafter described and claimed for carrying out the above stated objects and such other objects as will appear from the following description of certain preferred embodiments illustrated in the accompanying drawings, wherein—

Fig. 1 is a side elevational view of an apparatus embodying the principles of my

invention, certain parts being broken away to show the internal construction;

Fig. 2 is a view taken on the line 2—2 of Fig. 1, the motor having been removed;

Fig. 3 is a side elevational view of the apparatus, looking from a point to the left of Figs. 1 and 2, certain parts being broken away;

Fig. 4 is also a side elevational view of the apparatus with certain parts broken away, looking from a point to the right of the compressor shown in Figs. 1 and 2;

Fig. 5 is a sectional view, on the enlarged scale, taken on the line 5—5 of Fig. 2;

Fig. 6 is a sectional view taken on the line 6—6 of Fig. 5.

Figs. 7 and 8 are sectional views taken on the lines 7—7 and 8—8, respectively, of Fig. 3;

Fig. 9 is a perspective view of the spring employed for holding the crank shaft against longitudinal movement;

Fig. 10 is a perspective view of a portion of the packing ring employed to prevent leakage around the crank shaft of gas and oil from the crank case;

Fig. 11 is a sectional view, on an enlarged scale, taken on the line 11—11 of Fig. 2;

Fig. 12 is a sectional view, on an enlarged scale, taken on the line 12—12 of Fig. 11;

Fig. 13 is a side elevational view of the mechanism employed for controlling the inflow of water to the condenser; and

Fig. 14 is a sectional view taken on the line 14—14 of Fig. 13.

Like characters of reference designate like parts in the several views.

Referring now to the drawings and first to Fig. 1, it will be seen that the apparatus comprises a compressor 17, a condensing coil 18, an expansion valve 19 and an expansion coil 20 preferably placed in a brine tank 21 located in the refrigerator box, only the top wall 22 of the box being shown. The wall 22 is provided with an opening 23 in which the lower portion of a tank 24 containing the condensing coil is placed, said tank preferably being built into the base of the compressor and provided with a flange 25 to rest upon the wall 22.

The compressor is provided with cylinders 26 and 27 having pistons 28 and 29, respectively, connected by rods 30 to a crank shaft 31 journaled in bearings in the crank case 32 all of which may be of any desired construction. Each cylinder is provided with a head 33 and the compressor is provided with a head 34 which is hollowed out on its under side so as to provide a chamber 35 extending over the cylinder heads. The discharge end of the expansion coil 20 is fitted into the lower end of a passageway 36 provided in one wall of the tank 24. The cylinder block of the compressor is provided with passage-

ways 37, best shown in Fig. 3, leading from the passageway 36 to the chamber 35.

The valves for the cylinders are best shown in Fig. 11. Each cylinder head 33 is provided with external recesses 38 and 39, in which the inlet and outlet valves, respectively, are located.

The inlet valve arrangement includes a bushing 40, which is threaded into the recess 38 and is provided with internal longitudinal grooves 40^a, the lower end of the bushing terminating a short distance above the bottom of the recess. The cylinder head is provided with ports 41 to establish communication between the recess 38 and the cylinder. An inverted cup-shaped valve member 42 slides in the lower end of the bushing 40 and is provided with an outwardly, circumferentially extending flange 43. A compression spring 44 interposed between the under side of the valve member 42 and the bottom of the recess 38 normally holds the valve member with the upper surface of its flange seating against the lower end of the bushing.

The outlet valve arrangement includes a plug 45 which is threaded into the recess 39 and is provided with a recess 46 in its under side. Ports 47 are provided in the cylinder head to establish communication between the recess 39 and the cylinder. An inverted cup-shaped valve member 48 is slideable in the recess 46 in the plug and is provided with an outwardly, circumferentially extending flange 49 to cover the ports 47. A compression spring 50 is coiled about the valve member 48, being interposed between the under side of the plug and the upper side of the flange 49 to hold the valve normally closed.

A chamber 51, see Figs. 2, 4, 5, 6, 8 and 11, is preferably provided in the cylinder block, passageways 52 also being provided so that the compressed refrigerant may discharge through the respective outlet valves, the respective passageways 52 and into the chamber 51.

The means for relieving excessive pressure of the refrigerant will now be described. The compressor head 34 is provided with a recess 53, see Figs. 4, 5 and 11, the bottom of which is formed so as to provide a seat 54, a port 55 being provided to establish communication between the chamber 51 and the recess 53. A valve member 56 is placed in the recess 53 and the top of said recess is closed by a screw plug 57. A compression spring 58 is interposed between the under side of the plug 57 and the upper side of the valve 56 to hold the valve normally tight against the seat 54. The compressor head is provided with a passageway 59 to establish communication between the recess 53 and the chamber 35.

A chamber 60, see Figs. 2, 3 and 5, is pref-

- erably provided in the cylinder block in which the means for separating the oil from the refrigerant is located, the cylinder block also being provided with a passageway 61 leading from the chamber 51 to the chamber 60. The cylinder block is provided with passageways 62, best shown in Fig. 3, leading from the chamber 60 to a passageway 63 provided in one wall of the condenser tank, the inlet end of the condensing coil 18 being fitted into the discharge end of the passageway 63. The discharge end of the condensing coil is fitted into a passageway 64 leading to passageways 65 provided in one wall of the condenser tank. One end of a pipe 66 is fitted into the discharge end of the lowermost passageway 65, the other end of said pipe being connected to the expansion valve 19.
- 20 The means for separating the oil present in the refrigerant preferably comprises a plurality of inverted cone-shaped screens 67 of fine mesh which are mounted on a stem or rod 68. The passageway 61 leads into the chamber 60 at a point considerably above the bottom thereof so that the oil collected on the under sides of the screens 67 may drip and deposit in the bottom of the chamber without interfering with the inflow of 30 the refrigerant.
- The cylinder block is provided with a passageway 69, see Figs. 5 and 6, leading from the lower portion of the chamber 60 into a chamber 70, and a passageway 71 leads from the bottom of the chamber 70 into the crank case of the compressor so that the oil may flow from the chamber containing the oil separator into the crank case. A valve 72 is provided in the chamber 70 for controlling the passage of oil from the chamber 60 to the crank case, said valve oscillating about a shaft 73 and being provided with a port 74. A piston 75 is placed in the chamber 51 and is connected to the valve 72 by a rod 76, said piston being responsive to the pressure of the refrigerant in said chamber. The under side of the piston is provided with a pocket 77 in which a compression spring 78 is placed, the lower end of said spring resting on the bottom of the chamber 51. The parts are so arranged that, when the piston 75 is pressed down by the high-pressure refrigerant in the chamber 51, the mouth of the passageway 61 is uncovered and the valve member 72 is moved counter-clockwise in Fig. 6 and the mouth of the passageway 71 is closed; but, when the pressure of the refrigerant drops sufficiently, the spring 78 pushes the piston upwardly, closing the mouth of the passageway 61 and pulling the valve 72 around in a clockwise direction in said Fig. 6 to bring the port 74 into registry with the passageway 71.
- In order to permit the refrigerant which 60 leaks past the pistons into the cylinders and the crank case to escape therefrom, the cylinder block is provided with a passageway 79, see Fig. 1, leading from the cylinder 26 to one of the passageways 37; the mouth of the passageway 79 is located so that it is uncovered only when the piston in that cylinder is at substantially the end of its compression stroke.
- The means for preventing the escape of oil and particularly gas around the crank shaft from the crank case will now be described. One side of the crank case is provided with a cap 80, see Fig. 3, which fits over the adjacent end of the crank shaft so that the escape of oil and gas around the crank shaft at that side is effectively prevented. The other end of the crank shaft extends through a fitting 81 secured to the other side of the crank case, said fitting being provided with an inwardly, circumferentially extending flange 82 fitting around the crank shaft. That end of the crank shaft is provided with a shoulder 83. A yieldable, metallic, resilient packing ring 84, S-shaped in cross section, see also Fig. 10, is placed on the crank shaft, being interposed between the shoulder 83 and the inner face of the flange 82. A wearing washer 85 is preferably provided on the crank shaft at each side of the packing ring. A pulley 86 is mounted on the last mentioned end of the crank shaft. The opposite end of the crank shaft is recessed to provide a seat for a ball 87. A thrust spring member 88, see Fig. 9, is positioned within the cap 80 and carries a member 89 to provide a seat for the ball 87. The spring 88 thrusts the shaft in a direction to compress the packing ring 84.
- One wall of the tank 24 is provided with a passageway 90, see Fig. 1, through which the water may enter the condenser tank. The water circulates through the tank around the condensing coil and passes from the tank through passageways 91, see also Fig. 4, and discharges into a chamber 92 which surrounds the compressor cylinders, being formed by the jacket of the compressor. A baffle member 93 is preferably provided in the chamber 92 and is so arranged with respect to the discharge end of the passageway 91 that the water is given a whirling motion around the compressor cylinders. The water discharges from the chamber 92 through an overflow pipe 94 connected with passageways 95 which discharge into a pipe 96, see Fig. 2, leading to a drain.
- Admission of water to the condenser tank is controlled by a valve, designated generally by the reference numeral 97, see Figs. 1, 2, 13 and 14. The water flows from a pipe 98, connected with any source of supply, and passes into a chamber 99 provided in the valve casing, a seat 100 being provided therein for a valve 101. The valve

casing is also provided with a chamber 102 which connects with the passageway 90 leading to the condenser tank. A compression spring 103 normally holds the valve 101 closed.

- The means for automatically controlling the operation of the valve 97 includes a casing 104 provided with a chamber 105 across which a diaphragm 106 extends.
- 10 The chamber 105 connects with a passageway 107 leading to one of the passageways 65 which in turn is connected with the discharge end of the condenser coil. The diaphragm is connected to a slidable stem 108 which bears against one end of a pivoted lever 109, the other end of said lever bearing against the outer end of a slidable stem 110 connected with the valve 101. An adjustable member 111 bears against the lever 109, 20 said member being carried by a compression spring 112.

The compressor may be driven by any suitable power means, but preferably a motor 113 is employed. The motor is pivotally mounted on a base 114 which rests on the top of the condenser tank. The driving pulley 115 of the motor is connected by a belt 116 with the pulley 86 of the compressor. A rod 117 pivoted to the base 114

30 extends through a lug 118 formed on the side of the motor casing. By adjusting the nuts 119 on the rod the distance between the motor and compressor shafts may be varied and thus the belt may be tightened.

35 Operation: The refrigerant in a gaseous state is drawn from the expansion coil 20 through the low-pressure portion of the system, namely, the passageways 36 and 37, chambers 35, bushings 40, inlet valves, recesses 38, ports 41 and into the compressor cylinders, during the suction stroke of the pistons. On the return stroke of the pistons, the gaseous refrigerant is compressed, the outlet valves being forced off their re-

40 spective seats against the tension of the springs 50. The compressed refrigerant passes through the high-pressure portion of the system, namely, the recesses 39, passageways 52, chamber 51, passageway 61, oil

50 separator in the chamber 60, passageways 62 and 63, and into the condensing coil 18. The temperature of the compressed refrigerant is then substantially that of the cooling agent in the condenser tank. The refrigerant

55 liquefies and discharges into the passageways 64 and 65 and is then forced into the pipe 66, through the expansion valve 19 and into the expansion coil 20. The expansion valve is of any ordinary construction and has a pressure reducing opening, and, as the refrigerant

60 passes through this opening, a great reduction in pressure takes place. The refrigerant, consequently evaporates, resulting in a considerable reduction in temperature of the 65 refrigerating medium and, therefore, the

heat present in the brine, or other fluid or air surrounding the expansion coil, is extracted. The vapor is then returned to the compressor and the process is repeated continuously so long as the apparatus is in 70 operation.

When the apparatus ceases to operate, the pressure of the refrigerant in the high-pressure portion of the system which also includes 75 the passageways 65 and 107 and chamber 105, goes down and equalizes with that of the refrigerant in the low-pressure portion of the system. Under such conditions, the

80 spring 112 moves the lever 109 away from the stem 110 and the spring 103 holds the valve 101 closed and, therefore, the cooling agent does not circulate through the condenser tank and the chamber surrounding the compressor cylinders. However, when

85 the apparatus is in operation and the pressure of the refrigerant in the high-pressure portion of the system is relatively high, the pressure of the refrigerant against the diaphragm 106 forces it to move the lever 109 in a direction to unseat the valve 101. 90

Thereupon, water flows from the pipe 98, through chambers 99 and 102, passageway 90 and into the condenser tank where it circulates around the condensing coil and passes out through the passageways 91, into the

95 chamber 92, overflow pipe 94, passageways 95 and the outlet pipe 96. It will be observed, therefore, that the flow of the cooling agent through the condenser tank is automatically controlled and that there is 100

no opportunity for the refrigerant to escape around any of the parts and mix with the water, or for the water to escape and mix with the refrigerant. The water and refrigerant cannot possibly commingle. 105

Therefore, any sediment that may be present in the water cannot interfere with the operation of the diaphragm and its associated parts.

The bottom of the condenser tank being 110 located in the refrigerator box, the efficiency of the condenser is high because the cooling agent and the condensing coil are subject to the cold air in the box.

If the pressure of the refrigerant in the 115 high-pressure portion of the system should build up to too great an extent the relief valve 56 automatically opens and establishes direct communication between the high and low-pressure portions of the system.

At the end of each compression stroke of the piston 28 the mouth of the passageway 79 is uncovered which permits the high-pressure refrigerant, in the event it should leak around the pistons and get into the 120 crank case, to escape from the crank case and pass into the low-pressure portion of the system. This arrangement reduces the pressure in the crank case to a minimum, re-

duces the foaming of the oil in the crank case 125 130

to a minimum, aids in maintaining efficient lubrication of the working parts, and prevents any knocking of the pistons, connecting rods and the crank shaft which would 5 occur if back pressure developed, nevertheless the oil in the crank case is not permitted to escape therefrom.

The outlet valves of the cylinders operate substantially noiselessly because the compressed refrigerant flows under the valve members 48 as well as around them; consequently, the pressure under and around the valve members is equalized and they seat quietly.

15 It will be observed that the various passageways for the refrigerant and the water passing to and from the compressor and the condenser are drilled in the walls of the compressor and the condenser tank. The opportunity for leakage to occur is thus reduced to a minimum and a very compact construction is obtained.

The oil separator effectively removes substantially all the oil present in the compressed refrigerant and the oil thus obtained is returned to the crank case by means entirely automatic in its operation. When the apparatus is in operation, the pressure of the refrigerant in the chamber 51 forces 25 the piston 75 down thus causing the valve 72 to close the mouth of the passageway 71 which prevents the refrigerant from forcing the oil from the chamber 60 into the crank case and the refrigerant from passing 35 into the crank case. However, when the apparatus ceases to operate and the pressure of the refrigerant in the high-pressure portion drops sufficiently, the spring 78 pushes the piston up thereby closing the mouth 40 of the passageway 61 and positioning the valve 72 with its port 74 in register with the mouth of the passageway 71 so that the oil may flow under some pressure into the crank case.

45 I do not intend to limit my invention to the details of construction shown and described, except only in so far as certain of the appended claims are specifically so limited, as it will be obvious that modifications 50 may be made without departing from the principles of the invention.

I claim:

1. The combination of oil separating means, a chamber, a compressor for compressing a refrigerant through said means and chamber, means providing a passageway for returning the oil from said separating means to the crank case of the compressor, a valve in said passageway, a piston in said chamber connected with said valve for closing the same, and means, operable upon the refrigerant dropping to a predetermined point, for causing said piston to open said valve.

65 2. The combination of oil separating

means, a chamber, means providing a passageway from said chamber to said separating means, a compressor for compressing a refrigerant through said chamber, passageway and separating means, means providing a passageway for returning the oil from said separating means to the crank case of the compressor, and means for opening said first named passageway and closing said second named passageway or for 75 closing said first named passageway and opening said second named passageway.

3. The combination of oil separating means, a chamber, means providing a passageway from said chamber to said separating means, a compressor for compressing a refrigerant through said chamber, passageway and separating means, means providing a passageway for returning the oil from said separating means to the crank case of the compressor, and means in said chamber which operates, when the pressure of the refrigerant in said chamber exceeds a predetermined point, to open said first named passageway and to close said second 90 named passageway and, when the pressure of the refrigerant in said chamber drops below a predetermined point, to close said first named passageway and to open said second named passageway.

4. The combination of oil separating means, a chamber, means providing a passageway from said chamber to said separating means, a compressor for compressing a refrigerant through said chamber, passageway and separating means, means providing a passageway for returning the oil from said separating means to the crank case of the compressor, a valve in said last named passageway, and a piston in said chamber and connected with said valve, said piston operating, when the pressure of the refrigerant in said chamber exceeds a predetermined point, to open said first named passageway 100 and to close said valve, and, when the pressure of the refrigerant in said chamber drops below a predetermined point, to close said first named passageway and to open said valve.

5. The combination of oil separating means, a chamber, means providing a passageway from said chamber to said separating means, a compressor for compressing a refrigerant through said chamber, passageway and separating means, means providing a passageway for returning the oil from said separating means to the crank case of the compressor, a valve in said last named passageway, a piston in said chamber and connected with said valve, said piston 105 operating, when the pressure of the refrigerant in said chamber exceeds a predetermined point, to open said first named passageway and to close said valve, and means, operable upon the refrigerant dropping to a 110 predetermined point, for causing said piston to open said valve.

predetermined point, for causing said piston to close said first named passageway and to open said valve.

6. In the refrigerant circulatory system of a refrigerating apparatus including a low pressure portion and a high pressure portion, the combination of a compressor for compressing and circulating a refrigerant through said system, and means providing a 10 passageway leading from one of the cylinders of the compressor to the low pressure portion of said system, the mouth of said passageway being so located that it is uncovered only when the piston in said cylinder 15 is at substantially the end of its compression stroke.

7. The combination of a compressor for compressing a refrigerant, means for separating from said refrigerant oil which may be present therein, means providing a passageway leading from said oil separating means to the crank case of the compressor, and means actuated by the pressure of the refrigerant for wiping and closing said passageway when the pressure reaches a predetermined strength.

8. The combination of a compressor for compressing a refrigerant, means for separating from said refrigerant oil which may be present therein, means providing a passageway leading from said oil separating means to the crank case of the compressor, means movable across the end of said passageway for cleaning and closing it, and means controlled by the pressure of the refrigerant for operating said movable means.

9. The combination of a compressor for

compressing a refrigerant, means for separating from said refrigerant oil which may be present therein, means providing a passageway leading from said oil separating means to the crank case of the compressor, slidably mounted means adapted to move across the end of said passageway for cleaning and closing it, a piston adjacent to said 40 slidable means, a spring opposing the movement of the piston in one direction, and connections between the slidable means and the piston adapted upon the movement of the piston against said spring to move said 45 slidable means for closing said passageway.

10. In a refrigerating apparatus having means for circulating a refrigerant, the combination of a compressor, a crank for operating the compressor, means serving normally to exclude the refrigerant from the crank case, and means controlled by the operation of the compressor serving momentarily at intervals to open communication between the crank case and the low 50 pressure portion of said circulating means.

11. In a refrigerating apparatus having a refrigerant circulatory system, the combination of a compressor for delivering the refrigerant into the high pressure portion of said system, a crank for operating the compressor, means serving normally to exclude the refrigerant from the crank case, and means acting automatically at intervals 55 to open communication between the crank case and the low pressure portion of said 60 system.

DAVID POWELL.
